UNITED STATES PATENT OFFICE.

ROBERT W. POMMERER, OF NEW YORK, N. Y., ASSIGNOR OF ONE-HALF TO WILLIAM J. GILSEN,
OF NEW YORK, N. Y.

MEANS FOR USE IN BUILDING CONCRETE WALLS AND THE LIKE.

No. 878,155.

Specification of Letters Patent.

Patented Feb. 4, 1908.

Application filed August 4, 1906. Serial No. 329,151.

To all whom it may concern:

Be it known that I, ROBERT W. POMMERER, a citizen of the United States, and resident of the borough of Bronx, in the city 5 and State of New York, have invented a new and useful Improvement in Means for Use in Building Concrete Walls and the Like, of which the following is a specification.

The object of my present invention is to 10 provide an improved means for use in building concrete walls and the like whereby a vertical face for the wall may be insured by the use of a comparatively small number of trusses at a time, the construction of the 15 trusses being such that they may be readily shifted for each succeeding layer of concrete.

In the accompanying drawings, Figure 1 shows one of the trusses in full lines having its lower portion secured to the top layer of 20 a concrete wall or foundation, the series of bolts which are to be embedded in the next succeeding layer being shown attached to the upper portion of the truss and the position of the truss for the third layer being 25 shown in broken lines, Fig. 2 is an outside elevation of two adjacent trusses, and Fig. 3 is an inside elevation of two adjacent trusses.

The upper layer of the concrete wall or foundation is denoted by 1. To the face 2 30 of this wall or foundation is secured a plurality of trusses. Each truss comprises a vertical beam 3, upper and lower laterally extended planks 4, 5, laterally arranged diagonal braces 6, 7, and vertically arranged 35 diagonal braces 8, 9. A centrally arranged bolt 10 extends from the beam 3 outwardly and passes through the meeting ends of the lateral and vertical diagonal braces 6, 7, 8, 9, said bolt being provided with a nut 11 40 arranged to bring the proper strain on the truss for strengthening the beam 3.

Each of the braces and the beam 3 may be constructed of a plurality of pieces rigidly secured together, as shown, if so desired.

45 The laterally extended planks 4 and 5 are arranged to engage the face of the wall with the top of the upper laterally extended plank 4 substantially in alinement with the top of the upper layer of concrete.

50 The lower portion of the truss is removably engaged with a series of bolts 12, 13, 14,

which have been embedded in the concrete wall by causing the ends of the said bolts 12, 13, 14, to extend through the vertical beam 3 and providing the ends of the said bolts with 55 removable nuts 15, 16, 17, engaging the outer face of the said beam.

The upper portion of the truss has removably attached thereto a series of bolts 12*, 13*, 14*, corresponding to the lower series of 60 bolts 12, 13, 14, the upper series of bolts 12*, 13*, 14*, being arranged in position to be embedded in the next succeeding layer of concrete. After the layer of concrete in which the bolts 12*, 13*, 14*, are embedded, 65 has set, each truss will be removed from the upper and lower series of bolts by removing the nuts 15*, 16*, 17*, 15, 16, 17. Each truss will then be moved upwardly a step so that its lower portion will be caused to engage the upper series of bolts 12*, 13*, 14*. A new series of bolts is then removably placed in position in the upper portion of 70 each truss ready to be embedded in the succeeding layer of concrete. 75

From the above description it will be seen that instead of providing a trussed framework of the height of the wall to be built, a series of individual trusses arranged side by side may be utilized, each truss being only of 80 a sufficient height to guide the builders in the formation of the next succeeding layer. Furthermore, the trusses can be more easily handled and are more accurate than larger trusses and the trusses may be used over and 85 over again, the trusses only having to be supplied with new fastening bolts as required.

It is to be understood in use that the trusses are secured together side by side with 90 the ends of the upper and lower laterally extended planks 4, 5, in engagement with each other. These planks space the vertical beam 3 from the face 2 of the completed concrete layer thus leaving room for facing planks to 95 be inserted along the inner side of the upper portion of the beam 3 for retaining the next succeeding layer of concrete in position.

What I claim is:—

Means for use in building concrete walls 100 and the like consisting of a facing truss comprising a vertical beam, upper and lower

laterally extended planks, laterally and vertically arranged diagonal braces connecting said beam and said planks, means for securing the parts rigidly together and bolts re-
5 movably secured to the upper and lower por-
tions of the vertical beam.

In testimony, that I claim the foregoing as

my invention, I have signed my name in presence of two witnesses, this 2nd day of August 1906.

ROBERT W. POMMERER.
